FIG. 2

Raymond Barbas INVENTOR
BY Malvina
ATTORNEY, S.

UNITED STATES PATENT OFFICE

RAYMOND BARBAS, OF PARIS, FRANCE, ASSIGNOR TO LA SOCIÉTÉ ANONYME JEAN PATOU, OF PARIS, FRANCE, A CORPORATION OF FRANCE

DESIGN FOR A BOTTLE HOLDER

Application filed December 20, 1930. Serial No. 38,050. Term of patent 7 years.

To all whom it may concern:

Be it known that I, RAYMOND BARBAS, a citizen of the Republic of France, residing in the city of Paris, France, have invented a new, original, and ornamental Design for a Bottle Holder, of which the following is a specification, reference being had to the accompanying drawing, forming a part thereof.

In the drawing
Fig. 1 is a top plan view.
Fig. 2 is a front view.
I claim:
The ornamental design for a bottle holder substantially as shown.

R. BARBAS.
